UNITED STATES PATENT OFFICE.

JAMES C. WEIR, OF SAN FRANCISCO, CALIFORNIA.

BALL-CASTER.

SPECIFICATION forming part of Letters Patent No. 406,185, dated July 2, 1889.

Application filed September 4, 1888. Serial No. 284,584. (No model.)

To all whom it may concern:

Be it known that I, JAMES C. WEIR, a citizen of the United States, residing in the city and county of San Francisco, and State of California, have invented certain new and useful Improvements in Ball-Casters for Furniture, of which the following is a specification.

My invention relates to ball-casters for furniture, trunks, and other movable articles; and it consists in a certain novel construction and combination of parts, as hereinafter fully described, and pointed out in the claim.

Referring to the accompanying drawings that form a part of this specification, Figure 1 represents the caster applied to the leg of a piece of furniture. Fig. 2 is a vertical section, on a larger scale, of the ball-socket with the ball in place. Fig. 3 is a bottom view of the socket with the ball removed. Fig. 4 is a cross-section taken centrally through the half-spherical socket. Fig. 5 shows the roller-bearings in detail, and Fig. 6 shows the bottom plate in section. Fig. 7 shows one of the bearing-rollers in section.

The same letters of reference are used to denote corresponding parts in the several figures.

The half-spherical socket A is provided with a flange a, and the bottom plate B, corresponding in diameter with the socket-flange, fits closely upon it, so that the screws S S serve to hold the bottom plate, as well as to secure the socket in place. Bearing-points for the ball C are formed of a number of rollers D D^x, that are arranged in two sets in the socket, one above the other. The rollers of each set are strung on a hoop or ring E of cylindrical wire, on which they are mounted to turn loosely and also to slide longitudinally, and the two sets formed in the same manner, except that the lower set, being located at the bottom of the socket, has its ring of larger diameter than the one that carries the upper set of rollers. The interior of the socket is

divided into several recesses a², of uniform size, by means of the radial ribs A³ A³, that extend from the crown down to the flange, and the cavity being made sufficiently larger than the ball C for this purpose, the edges of the ribs clear the surface of the ball. These ribs serve the double purpose of spacing the rollers and furnishing supporting-points for the rings. Notches E^x are cut in the edges of the ribs to receive the rings, and at these points around the circle each ring is held out at suitable distance from the interior surface of the socket-cavity to keep the rollers clear and cause them to turn freely, while the rollers themselves are of suitable diameter to bear on the surface of the ball and keep it clear of contact at all points within the socket. As thus constructed and arranged, the rollers are free to slip on the rings E, as well as to rotate under the various motions of the ball; but the sliding movements are limited by the ribs A³, so that the rollers are separated and properly spaced to distribute the bearing-points equally around the ball during all its motions in the socket.

A caster constructed in this manner can be made exceedingly light, and yet capable of sustaining considerable weight.

Having thus fully described my invention, what I claim, and desire to secure by Letters Patent, is—

The herein-described ball-caster, consisting of the socket A, having the separate internal recesses a² and the flange a, the bottom plate B, ball C, and the bearing-rollers D D^x, mounted on hoops E, all constructed and combined for operation as set forth.

In testimony that I claim the foregoing I have hereunto set my hand and seal.

JAMES C. WEIR. [L. S.]
